UNITED STATES PATENT OFFICE.

WILLIAM D. FORSYTH, OF YOUNGSTOWN, OHIO, ASSIGNEE, BY MESNE ASSIGNMENTS,
TO RAILWAY PRODUCTS CORPORATION, OF BUFFALO, NEW YORK, A CORPORATION
OF NEW YORK.

CAR-TRUCK SIDE FRAME.

1,125,289.

Specification of Letters Patent.

Patented Jan. 19, 1915.

Application filed June 23, 1913. Serial No. 775,218.

To all whom it may concern:

Be it known that I, WILLIAM D. FORSYTH, a citizen of the United States, residing at Youngstown, in the county of Mahoning and

5 State of Ohio, have invented new and useful Improvements in Car-Truck Side Frames, of which the following is a specification.

The principal object of my invention is to provide an improved car truck side frame 10 in which the bolster guide bars are made in one piece.

Further objects are to attain certain other advantages as will be more fully set forth hereinafter.

15 The invention consists in a car truck side frame in which the bolster guide bars are made in one piece, preferably from a rolled section.

In the accompanying drawings, which 20 form part of the specification, and in which like reference characters refer to like parts throughout the several views, Figure 1 is a side elevation of a car truck side frame embodying my invention; Fig. 2 is a top plan 25 view of the side frame shown in Fig. 1; Fig. 3 is a cross-section on the line A—A on Fig. 1; Fig. 4 is a cross-section on the line B—B on Fig. 1; Fig. 5 is a cross-section on the line C—C on Fig. 1; Fig. 6 is a front 30 elevation of the bolster guide frame; Fig. 7 is a vertical section on the line D—D on Fig. 6; Fig. 8 is a vertical section of a bolster guide frame showing a modified construction.

35 For the purpose of illustration I have shown the bolster guide frame 3 embodying my invention as applied to a car truck side frame in which the compression member 1 and the tension member 2 are each made of 40 a single piece of metal; but it is to be understood that my invention is not limited to this application. The compression member 1 is preferably made from a piece of metal, rolled, forged or pressed into a channel 45 shape, and has a web 5 with flanges 6, and is arched in the manner shown in Fig. 1. The tension member 2 is preferably also made from a channel shape, and has a web 9 and flanges 11 between the points 10 where 50 it is attached to the compression member 1. The flanges 11 are made of a varying width, as shown. The ends of the compression member 1 and the ends of the tension member 2 are provided with holes 13 for the 55 bolts which fasten the journal boxes to the

side frame. Brackets 4 are riveted to the web 9 of the tension member 2 on each side of the side frame, and have holes 13^a for the journal box bolts.

The bolster guide frame 3 is preferably 60 made from a rolled, forged or pressed shape. In its finished form, the bolster guide frame 3 has a web 14 and spaced parallel flanges 16. The flanges 16 are spaced so that the compression member 1 and the tension member 65 2 fit between them, and at the top of the bolster guide frame 3 the flanges 16 are fastened by rivets 8 to the flanges 6 of the compression member 1, and at the bottom to the flanges 11 of the tension member 2 by rivets 70 12. The bolster guide frame 3 has an opening 17 adapted to receive a bolster, and this opening 17 is narrower at the top than at the bottom. The bolster guide frame 3 is made from a structural shape having a web 75 14 and two spaced flanges 16 located between the edges of the web, as shown at the bottom of Fig. 7. This structural shape is bent along transverse lines so as to form an open frame having the opening 17 therein, 80 and the ends of the structural shape are brought together, as indicated by the dotted line 7 on Fig. 6 at the middle of one of the sides. These abutting ends may be welded together. The edges of the structural shape 85 from which the bolster guide frame 3 is made are cut away, as indicated in dotted lines in Fig. 7, to give the desired shape to the finished bolster guide frame.

In the modified form of construction 90 shown in Fig. 8, the bolster guide frame 3 is made from two pieces 18 of rolled, forged or pressed structural shape which are substantially T-shape in cross-section. These pieces 18 have a body portion 19 and a web 95 or fin 20. Each piece is bent along transverse lines to form an open frame, and the edges of the body portions 19 are brought together and welded, as indicated by the line 22. The other edges 21 of the body portion 100 19 are cut away, as indicated in the dotted lines on Fig. 8, to give the desired shape to the bolster guide frame.

According to my invention, a strong and 105 light bolster guide frame may be cheaply made from rolled or pressed structural shapes. A bolster guide frame made from a structural shape is stronger and lighter than a cast frame, and will have smoother surfaces than a cast frame. 110

Obviously, the structure which I have shown and described may be considerably modified without departing from my invention, and I do not wish, therefore, to be limited to this exact construction.

What I claim as my invention is:

1. A car truck side frame comprising a channel-shaped compression member and a tension member having spaced flanges thereon at its middle portion, said compression member and said tension member being spaced apart at their middles, a bolster guide frame comprising a structural shape having parallel flanges thereon and bent along transverse lines into a frame having a bolster opening therein, the ends of said structural shape being brought together at the middle of one of the sides of said frame and welded, the flanges on said bolster guide frame being riveted to the sides of said channel-shaped compression member at its

middle and to said flanges on said tension member.

2. A car truck side frame comprising a compression and a tension member spaced apart at their middle portions, a bolster guide frame comprising a structural shape having parallel flanges thereon and bent along transverse lines into a quadrilateral frame having a bolster opening therein, the flanges of said bolster guide frame being riveted to said middle portions of said compression and tension members on opposite sides thereof.

In witness whereof I have hereunto subscribed my name in the presence of two subscribing witnesses.

WILLIAM D. FORSYTH.
